(57) **CLAIM**

The ornamental design for a digital night vision device, as shown and described.

DESCRIPTION

FIG. 1 is a first perspective view of a digital night vision device showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The evenly dashed broken lines shown in the drawings depict portions of the digital night vision device that form no part of the claimed design. The unevenly dashed broken lines in FIGS. 2 and 9 demarcate the boundaries of the enlarged view and form no part of the claimed design
